AUTOMATIC TELEPHONE DIAL SYSTEM

Joseph Lobel, Bronx, N. Y.

Application October 20, 1942, Serial No. 462,672

6 Claims. (Cl. 179—90)

This invention relates to new and useful improvements in an automatic telephone dial system.

More particularly, the invention proposes a system whereby each one of a selected group of telephone numbers may be dialed by depressing but one button. It is proposed that a device embodying this new system be hooked up with the telephone circuit of a dial telephone, and that it have a plurality of depressible buttons, and that each button represent a particular telephone number. These numbers may be called by depressing and releasing the buttons. This contrasts with the present system whereby the dial must be operated seven times to call a number.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of an automatic telephone calling device constructed according to this invention.

Fig. 2 is an enlarged vertical sectional view taken on the line 2—2 of Fig. 1.

Fig. 3 is a fragmentary enlarged vertical sectional view taken on the line 3—3 of Fig. 2.

Fig. 4 is a fragmentary vertical sectional view taken across the back of the front wall of one of the switches shown in Fig. 2, this view being as though taken on the line 4—4 of Fig. 2.

Fig. 5 is a fragmentary enlarged vertical sectional view taken on the line 5—5 of Fig. 6.

Fig. 6 is a horizontal sectional view taken on the line 6—6 of Fig. 2.

Fig. 7 is a perspective view of one of the parts shown in Fig. 6.

Fig. 8 is a fragmentary vertical sectional view taken on the line 8—8 of Fig. 2.

Fig. 9 is a schematic wiring diagram of the device.

The automatic telephone dial system, in accordance with this invention, includes a plurality of selectively depressible code rods 10 of electric conductive material having a plurality of spaced insulation pieces 11 along their lengths representing different telephone numbers. Each code rod 10 threadedly engages through a pair of spaced collars 12. These collars 12 each have a pair of projecting lugs 13 which slidably engage in inclined slots 14 formed in a pair of flanges 15 which project from the inner face of a cylin-

der 16. This cylinder 16 is mounted upon a frame 17 which is supported in a cylindrical box or container 18. Springs 19 are connected with the collars 12 and with pins 20 mounted upon the cylinder 16 for normally urging the code rods 10 upwards. The container 18 is provided with a cover 21 through which depressible buttons 22 extend. There is one button for each code rod 10. These buttons 22 have stems 23 of insulation material which rests upon the tops of the code rods 10. Adjacent to each button 22 there is a small frame 24 mounted on the cover 21 for a name plate with a telephone number. The buttons 22 may be depressed one at a time each, for calling a number, as will become clear as this specification proceeds.

Dashpot dampened solenoid operative means is provided for catching and holding depressed any one of the code rods 10. This means includes a solenoid 25 for each code rod 10 which is mounted upon the cylinder 16. Each solenoid 25 has an extendable core plunger 26, the front end of which is provided with a piece of insulation 27 which engages against the side of the code rod 10. Each metering rod 10 has a circumferential groove 28 which is aligned with the end 27 of its solenoid rod 26 when the code rod 10 is in its depressed position. The code rod 10 at the right is shown engaged and held depressed by the core 26 of the solenoid 25. The code rod 10 at the left is shown in its raised position.

Each solenoid 25 is associated with a dashpot 28 located upon its back. The core 26 of each solenoid 25 passes through the dashpot, which includes a cylinder 29 in which a piston 30 is slidably mounted. This piston 30 is mounted on the solenoid rod 26. A spring 31 urges the piston 30 outwards. The piston 30 is provided with openings 30^a normally closed by a flexible rubber disc 32 in the nature of a valve. The cylinder 29 is provided with openings 33 at its outer end. The construction is such that when the solenoid 25 is energized, the rod 26 and piston 30 may move forwards rapidly. During this action the rubber disc 32 flexes, allowing the air to pass from the inner end of the cylinder 29 to the outer end. However, the spring 31 can move the piston 30 outwards at a slow rate only, depending on the entrance of air into the inner end of the cylinder 29 through bleed openings 32^a in the valve disc 32. The dashpots 28 are supported on a partition 34 mounted within the container 18.

An electric motor driven conductor 35 is adapted to move along the depressed code rod 10 and alternately engages portions of said rod 10 and its insulation pieces 11. This conductor 35 com-

prises a conductor ring which is mounted upon an annular insulation member 35 held slidably and non-rotative by a stationary rod 37' and which threadedly engages a screw 37 rotatively supported and driven by a motor 38. The slot 14 of the flanges 15 slopes downwards and towards the screw 37. The arrangement is such that in the depressed position of the code rod 10, the conductor 35 engages against its side.

The motor 38 is controlled by a reversing switch 39 which is operated by a rod 40 slidably supported in bearings 41 which are mounted upon the cylinder 16. The rod 40 is provided with an inturned top end 41 and which is engaged by the annular member 36 when it is in its top position. The rod 40 is also provided with a projection 43 which is engaged by the annular member 36 when it is substantially in its bottom position.

Beneath each code rod 10 there is a combination start and stop switch 44. This switch 44 has a depressible head 45, which when depressed closes the switch. It is also provided with a laterally projecting lever 46, which when depressed opens the switch. A spring 47 normally urges the head 45 into a raised position. Another spring 48 normally urges the lever 46 into a raised position. The motor 38 is associated with a normally open start switch 49 which is closed by a projection 50 on one of the cores 26 of one of the solenoids 25 when the solenoid is deenergized.

There is another stop switch 51 for the electric motor 38. This switch 51 is located upon the frame 17 at a position to be engaged by a projecting rod 52 mounted on the annular insulation member 36. The annular insulation member 36 is also provided with downwardly extending rods 53 which are adapted to strike the levers 46 for operating the switches 44 when the annular member 36 is in its bottom position. The switch 51 has a head 54 which must be lifted to open the switch. A spring 55 urges the head 54 downwards. The 54 is connected with a conductor 56 which in a closed position of the switch engages the contacts 57 for closing the circuit through the switch. Each code rod 10 is provided with contacts 58 engageable with an insulated conductor plate 59 located at the bottom of the cylinder 16 and comprising a ground connection for the device and separated from the cylinder 16 by an insulation ring 16'.

Each code rod may be disengaged from the collars 12 merely by unscrewing it. When removed, nuts 10' at the bottom portions of the code rods may be unscrewed. This frees the insulation pieces 11. The insulation pieces 11 are merely in the form of insulation rings. They are separated from each other by conductor material rings 10^a which directly engage the code rod 10 so that there is a closed circuit from the conductor 35 to the code rod 10 as the conductor 35 alternately passes over the insulation pieces 11 and the conductive rings 10^a.

The telephone circuit 60 has the usual switch 61 which is closed when the receiver is lifted off the hook. This circuit 60 is connected in series with a parallel circuit 62 connecting in parallel the various coils of the solenoids 25 and then at the point 63 continuing in a series and connecting with the conductor 35, the depressed code rod 10, the plate 59, and the return of the telephone circuit 60. It should be noted that the telephone circuit will be interrupted and broken as the contact 35 passes over the various insula-

tion pieces 11, and this interruption is designed to set the dialing mechanism into operation and connect a number which is represented by the particular depressed code rod 10.

5 The conductor 35 moves along its path because it is moved by the annular insulation member 36 which is driven by the screw 37. The screw 37 is driven by the motor 38 which is controlled in the following way.

10 The source of electric power for the motor 38 is schematically represented by the battery 64 supplying the circuit 65. Included in series with the circuit 65 is a parallel connection of the combination switches 44 and then continuing in series, the reversing switch 39 which is arranged to reverse the direction of flow in the shunt 66 of the motor 38. Because the combination switches 44 are arranged in parallel in the series connection, the series circuit will be closed

15 when any one of the switches 44 is closed. When one of the code rods 10 is depressed one of the switches 44 will be closed and the circuit through the motor 38 is therefore closed to operate the motor. The motor will turn in a direction depending upon the position of the reversing switch 39, and this switch 39 will be in a position to cause the motor 38 to drive the screw 37 in a direction in which the annular insulation member 36 moves downwards. The motor will continue

20 operating in this direction until one of the rods 53 strikes the handle 46 of the closed combination switch 44, opening the same. This stops the motor 38 and the telephone number has been dialed, and when the connection is made the telephone conversation may proceed.

25 The parts remain in above said positions until the telephone circuit 60 is broken by the switch 61 which is open when the telephone receiver is replaced on the hook. When the telephone circuit is thus broken the solenoids 25 will become deenergized and the springs 31 of the dashpots will slowly move out the cores 26. The purpose of the dashpots 28 is to dampen the actions of the solenoids 25 so that the depressed

30 code rod 10 is not released by the solenoid cores 26 while the telephone circuit is being momentarily interrupted by the conductor 35 passing the insulation pieces 11. However, when the telephone circuit remains open for a sufficient length of time the cores 26 of the solenoids will become fully retracted. The core 26 provided with the projection 50 will close the switch 49. This will restart the electric motor 38. However, the motor will now operate in a reverse direction be-

35 cause when the insulation member 36 reached its bottom-most position it engaged against the projection 43 and moved the rod 40 which threw the reversing switch 39 in the opposite direction.

40 The switch 49 is connected in series with the switch 51 and this series connection shunts the combination switches 44. Since the switch 51 is closed because the annular member 36 is down, and since the switch 49 is now closed by the pro-

45 jection 50, the motor 38 will start functioning. It will continue to function until the annular member 36 reaches its top position, at which instant it strikes the projection 42 of the rod 40 throwing the switch 39 back to its original position and 50 setting the motor ready to operate in the opposite direction. However, at this instant the rod 52 opens the switch 51 and stops the motor 38. The motor 38 will remain stopped until another one of the code rods 10 is depressed. It is pointed out that when the cores 26 of the various

solenoids became retracted, the depressed code rod 10 was released and was immediately moved to its raised position by the springs 19. The device is now in its original condition ready to be re-operated.

The operation of the device is as follows:

Any one of the buttons 22 may be depressed for obtaining a telephone connection with any one of the numbers designated by the card in the frame 24 adjacent a button 22. When desired these numbers may easily be changed by first removing the cover 21 and then screwing out any particular code rod 10 and replacing the metering rod with a new code rod in which the insulation pieces 11 are arranged to control the dialing system of the new number.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. An automatic telephone dial system, comprising a plurality of selectively depressible code rods of electric conductive material having a plurality of spaced insulation pieces along their lengths representing different telephone numbers, dashpot damped solenoid operative means for catching and holding depressed any one of said code rods, an electric motor driven conductor for moving along the depressed code rod alternatively engaging portions of said rod and its insulation pieces, a telephone circuit including in series said depressed code rod and solenoid operative means and said conductor, reversing switch means for the motor of said electric motor driven contact for alternately reversing said motor when said contact reaches the ends of said code rod, stop switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod.

2. An automatic telephone dial system, comprising a plurality of selectively depressible code rods of electric conductive material having a plurality of spaced insulation pieces along their lengths representing different telephone numbers, dashpot damped solenoid operative means for catching and holding depressed any one of said code rods, an electric motor driven conductor for moving along the depressed code rod alternatively engaging portions of said rod and its insulation pieces, a telephone circuit including in series said depressed code rod and solenoid operative means and said conductor, reversing switch means for the motor of said electric motor driven contact for alternately reversing said motor when said contact reaches the ends of said code rod, stop switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod, said code rods being removable for changing the numbers to be dialed.

3. An automatic telephone dial system, comprising a plurality of selectively depressible code rods of electric conductive material having a plurality of spaced insulation pieces along their lengths representing different telephone numbers, dashpot damped solenoid operative means for catching and holding depressed any one of said code rods, an electric motor driven conductor for moving along the depressed code rod alternatively engaging portions of said rod and its insulation pieces, a telephone circuit including in series said depressed code rod and solenoid operative means and said conductor, reversing switch means for the motor of said electric motor driven contact for alternately reversing said motor when said contact reaches the ends of said code rod, stop switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod, said code rods being removable for changing the numbers to be dialed, each code rod comprises a plurality of conductive rings separating said insulation pieces, said insulation pieces being of ring form.
4. An automatic telephone dial system, comprising a plurality of selectively depressible code rods of electric conductive material having a plurality of spaced insulation pieces along their lengths representing different telephone numbers, dashpot damped solenoid operative means for catching and holding depressed any one of said code rods, an electric motor driven conductor for moving along the depressed code rod alternatively engaging portions of said rod and its insulation pieces, a telephone circuit including in series said depressed code rod and solenoid operative means and said conductor, reversing switch means for the motor of said electric motor driven contact for alternately reversing said motor when said contact reaches the ends of said code rod, stop switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod, said code rods being removable for changing the numbers to be dialed, each code rod comprises a plurality of conductive rings separating said insulation pieces, said insulation pieces being of ring form.
5. An automatic telephone dial system, comprising a plurality of selectively depressible code rods of electric conductive material having a plurality of spaced insulation pieces along their lengths representing different telephone numbers, dashpot damped solenoid operative means for catching and holding depressed any one of said code rods, an electric motor driven conductor for moving along the depressed code rod alternatively engaging portions of said rod and its insulation pieces, a telephone circuit including in series said depressed code rod and solenoid operative means and said conductor, reversing switch means for the motor of said electric motor driven contact for alternately reversing said motor when said contact reaches the ends of said code rod, stop switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod, said code rods being removable for changing the numbers to be dialed, each code rod comprises a plurality of conductive rings separating said insulation pieces, said insulation pieces being of ring form, and a nut for releasably holding said insulation pieces and conductive rings in position.
6. An automatic telephone dial system, comprising a plurality of selectively depressible code rods of electric conductive material having a plurality of spaced insulation pieces along their lengths representing different telephone numbers, dashpot damped solenoid operative means for catching and holding depressed any one of said code rods, an electric motor driven conductor for moving along the depressed code rod alternatively engaging portions of said rod and its insulation pieces, a telephone circuit including in series said depressed code rod and solenoid operative means and said conductor, reversing switch means for the motor of said electric motor driven contact for alternately reversing said motor when said contact reaches the ends of said code rod, stop switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod, said code rods being removable for changing the numbers to be dialed, each code rod comprises a plurality of conductive rings separating said insulation pieces, said insulation pieces being of ring form, and a nut for releasably holding said insulation pieces and conductive rings in position.
7. An automatic telephone dial system, comprising a plurality of selectively depressible code rods of electric conductive material having a plurality of spaced insulation pieces along their lengths representing different telephone numbers, dashpot damped solenoid operative means for catching and holding depressed any one of said code rods, an electric motor driven conductor for moving along the depressed code rod alternatively engaging portions of said rod and its insulation pieces, a telephone circuit including in series said depressed code rod and solenoid operative means and said conductor, reversing switch means for the motor of said electric motor driven contact for alternately reversing said motor when said contact reaches the ends of said code rod, stop switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod, said code rods being removable for changing the numbers to be dialed, each code rod comprises a plurality of conductive rings separating said insulation pieces, said insulation pieces being of ring form, and a nut for releasably holding said insulation pieces and conductive rings in position.

switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod, said dashpot damped solenoid operative means including solenoids the cores of which are connected with dashpots.

6. An automatic telephone dial system, comprising a plurality of selectively depressible code rods of electric conductive material having a plurality of spaced insulation pieces along their lengths representing different telephone numbers, dashpot damped solenoid operative means for catching and holding depressed any one of said code rods, an electric motor driven conductor for moving along the depressed code rod alter-

natively engaging portions of said rod and its insulation pieces, a telephone circuit including in series said depressed code rod and solenoid operative means and said conductor, reversing switch means for the motor of said electric motor driven contact for alternately reversing said motor when said contact reaches the ends of said code rod, stop switches for said motor when said contact reaches the bottom end of said code rod, a start switch for said motor operated by said dashpot damped solenoid operative means when the telephone circuit is broken more than a certain time interval, and another stop switch for said motor when said contact reaches the top end of said code rod, said reversing switch means including a reversing switch and an operator rod moved by said driven conductor as the conductor reaches the ends of its stroke.

JOSEPH LOBEL.
